SHIELD FOR HOT AIR REGISTERS OR THE
LIKEWilliam A. Wiesman, Dayton, Ohio, assignor of
one-half to Ralph F. Behringer, Dayton, Ohio

Application April 27, 1931. Serial No. 533,011

20 Claims. (Cl. 98—108)

This invention relates to a shield for a hot air register or the like and one object of the invention is to provide such a shield which may be moved to a position in which it will serve as a closure or cut-off to prevent the passage of hot air through the register.

A further object of the invention is to provide such a device in which the shield, when in the position to serve as a cut-off, will extend substantially parallel with the grille of the register in a position close thereto.

A further object of the invention is to provide such a device with a flexible shaft having means to support the same in an upwardly and forwardly curved position above the grille or in a position below the grille where it will serve as a cut-off.

A further object of the invention is to provide such a device with means controlled by the movements of the shield to close the spaces between the sides of the shield and the grille.

A further object of the invention is to provide such a device with means for controlling the movements of the shield and retaining the same in adjusted positions.

Other objects of the invention will appear as the device is described in detail.

In the accompanying drawings Fig. 1 is a top plan view of a hot air register embodying my invention, partly broken away; Fig. 2 is a longitudinal sectional view taken through such a register; Fig. 3 is a section taken on the line 3—3 of Fig. 2, with the shield in its lowered position; Fig. 4 is a detail sectional view on the line 4—4 of Fig. 2; and Fig. 5 is a detail view of the means for controlling the movement of the shield supporting members and the closure devices.

In these drawings I have illustrated one embodiment of my invention and have shown the same as applied to a hot air register which comprises a housing 6 adapted to be mounted in the upper end of a hot air duct 7. This housing is preferably of sheet metal and has at its upper end an outwardly extending flange 8 to overlie the floor 9, at the top of the air duct and support the housing thereon. Arranged above the housing is a grille 10 which is supported at its edges on the floor and is provided in the lower surface of its marginal portions with grooves 11 to receive the flanges 8 of the housing. This grille is provided near one end with a transverse slot 12 of a length substantially equal to the width of the housing and is further provided near its lateral edges with longitudinal slots 13 extending for somewhat more than half the

length of the grille and communicating with the transverse slot 12. The rear end of the grille, between the longitudinal slots 13, is supported by means of lugs 14 depending therefrom and resting upon a transverse bearing 15 rigidly mounted in the side walls of the housing. In the present construction, where the outer portions of the grille overhang the flanges of the housing, the slots are formed in the body of the grille but it will be obvious that the slots may be arranged to accommodate the same to different arrangements of the grille and of the housing.

Mounted on the housing for movement through the transverse slot 12 is a shield 16 of such a character that it may be moved into an upwardly and forwardly curved position above the rear portion of the grille, where it will extend between the register and a wall adjacent to the rear end of the register and which may be moved into a position below the grille in which it will extend across the housing and close the air duct 7. Preferably this shield is of a flexible character which will permit it to assume different shapes when it is positioned above or below the grille. As here shown, it

comprises a plurality of strips 17 extending transversely to the shield and arranged edge to edge and flexibly connected one to the other. These strips are preferably of thin sheet metal and are connected one to the other by means of wires 18 extending across the several strips, on the inner surfaces thereof, and secured thereto by means of clips 19. As here shown, these clips are in the form of short loops of metal struck inwardly from the respective strips and through which the wire extends. The outer end of the flexible shield is supported by suitable supporting members here shown as bars or plates 20 pivotally mounted on studs 21 extending inwardly from the side walls of the housing 6 below the grille 10. These supporting bars extend through the longitudinal slots 13 and are rigidly secured at their outer ends to the foremost strip 17 of the shield. This foremost strip preferably has its forward edge curved downwardly and rearwardly, as shown at 22.

Suitable guides are arranged within the housing to guide the shield into the desired position when it is moved to its lowermost or cut-off position. In the present construction these guides are in the form of rods 23 rigidly mounted within the housing adjacent to the respective sides thereof and having their rear ends curved upwardly, as shown at 24, and termi-

nating below and adjacent to the transverse slot 13. The several strips constituting the shield have their end portions curved inwardly, as shown at 25, to embrace the guide rods 23.

5 The length of the shield is such that when in its extended position, above the grille, with the supporting members in substantially vertical positions, a portion of the shield will remain beneath the grille and in supporting engagement 10 with the curved ends 24 of the guide rods. The guide rods are straight and substantially horizontal for the greater portion of their length and when rearward pressure is applied to the forward end of the shield it will slide downwardly and be guided along the rods 23 to a substantially horizontal position within the housing and spaced a relatively short distance below the grille, thus enabling the housing to be of relatively shallow depth.

20 Collapsible closures are provided to close the space between the side portions of the shield, when in its extended position, and the grille. As here shown, each of these closures comprises a plurality of plates 26, pivotally supported on 25 the housing and so arranged that they may be moved into substantially parallel positions below the surface of the grille or into extended positions in which they will close the spaces at the sides of the shield. In the present construction, the plates 26 of each closure are pivotally mounted on the studs 21 which carry the shield supporting members 20 and the outer ends of the plates overlap the inwardly bent portions or flanges of the several sections of 30 the shield. Preferably the several plates are tapered from their outer ends toward their axes and have approximately the shape of sectors. The movement of these closure plates to their collapsed or extended positions is controlled by 35 40 the movement of the shield as a whole and, in the form here shown, the supporting bars 20 have inwardly extending flanges 27 which overlap the edges of the several plates of the adjacent closure so that when the shield and supporting members are moved rearwardly and 45 downwardly these flanges will successively engage the edges of the several closure plates and will cause these to move downwardly into folded positions. Each closure plate has a part 28 50 extending below its axis and arranged in the path of the lower portion of the flange 27 of the adjacent shield supporting bar so that when the supporting bars and shield are moved upwardly and forwardly the lower portions of 55 the flanges 27 will engage parts 28 of the closure plates and cause these plates to move with the shield to their extended positions. The parts 28 of the several plates of each closure are of 60 different widths and are so arranged that they will be engaged successively by the flange 27 and the several closure plates will be successively actuated and will be moved different distances, the arrangement preferably being such that the adjacent edges of the plates will slightly overlap when in their extended positions. Each of the closure plates 26 has at or near 65 the outer end of its forward edge a cut-away portion or recess 27a to receive the inturned edge 22 of the foremost plate 17 and thus permit the several closure plates and the supporting bars 20 to be moved into parallel positions in which they will be compactly arranged, the upper edges of these plates and bars, when in 70 their collapsed position, being adjacent to or just below the surface of the grille. I have 75

also shown light springs 29 mounted in the housing and engaging the innermost plate 26 of each closure to press the same outwardly and, because of the overlapping arrangement of the several plates, to press each inner plate 80 toward the succeeding outer plate, thus retaining the plates in snug contact one with the other.

Any suitable means may be provided for retaining the shield in adjusted positions. In 85 the present construction, each supporting bar 27 has a sector shaped portion 30 projecting below its axis and provided near its forward edge with an opening 31. Rigidly mounted in the housing adjacent to the segmental part 90 95 of each supporting bar is a pair of resilient fingers 32 which embrace the segmental part of the bar and are here shown as provided with opposed indentations 33 which firmly grip the segment and retard its movement in either direction, the gripping action being sufficient to hold the shield in any position to which it may be moved. When the shield is moved to its foremost position the openings 31 in the segments 30 are brought into line with the indentations 33 and these indentations enter the respective openings, thus providing a very firm lock to hold the shield in its foremost position but which will yield under pressure to release the shield for rearward movement. To prevent the shield from being moved too far forward and the openings 31 carried past the indentations 33 the inner finger 32 of each pair is provided with a shoulder 34 arranged in the path of the lower end of the flange 27 of the 100 adjacent supporting bar 20 and so positioned that it will be engaged by that flange when that bar is moved to its foremost position.

In order to prevent any tendency of the shield to buckle when it is moved rearwardly 115 and to cause the same to move smoothly along the guide rods I have connected a spring with the lower portion of the shield, within the housing, which is so arranged that it tends to move the lower portion of the shield toward 120 that end of the housing opposite the transverse slot 12. In the present construction, this spring is in the form of a clock spring 35 coiled about a stud or rod 36 at the forward end of the housing extending rearwardly along the 125 guide rods 23 and secured at its free end to one of the lower sections of the shield. Consequently this spring at all times exerts a rearward action on the lower portion of the shield which prevents the same from binding on the 130 guide rods and eliminates any tendency of the shield to buckle.

While I have shown and described one embodiment of my invention I wish it to be understood that I do not desire to be limited to the 135 details thereof as various modifications may occur to a person skilled in the art.

Having now fully described my invention, what I claim as new and desire to secure by Letters Patent, is:

1. In a hot air register, a grille, a flexible shield mounted for movement into an extended position above said grille with its forward edge spaced therefrom and into a transverse position below and adjacent to said grille, and a guide engaging said shield to flex the same as it moves from one position to the other.

2. In a hot air register, a grille, a flexible shield mounted for movement into a position in which it will extend upwardly and forwardly 150

- from the rear edge of said grille and into a position below said grille, and a guide engaging said shield to flex the same as it moves downwardly to cause the major portion thereof to 5 assume a substantially flat position beneath said grille. 80
3. In a hot air register, a housing, a grille having a slot near one end thereof, a flexible shield movable through said slot, movable 10 means for supporting said shield in an extended position with its upper end above an intermediate portion of said grille, and means for flexing said shield as it is moved downwardly through said slot and to guide the major portion thereof into a substantially flat position 15 across said housing below said grille. 85
4. In a hot air register, a housing, a grille having a slot near one end thereof, a flexible shield movable through said slot to positions 20 above and below said grille, and supporting members pivotally mounted on said housing at points spaced from said slot and having supporting connection with the outer end of said shield. 90
- 25 5. In a hot air register, a housing, a grille having a slot near one end thereof, guides arranged below said grille, a flexible shield slidably supported on said guides for movement through said slot, and supporting members pivotally supported on said housing at points spaced 30 from said slot and having supporting connection with the outer end of said shield. 95
6. In a hot air register, a housing, a grille having a slot near one end thereof, guides arranged in substantially horizontal positions beneath said grille and having those ends adjacent to said slot curved upwardly, a flexible shield slidably mounted on said guides for movement through said slot, and bars pivotally 40 mounted at the respective sides of said housing at points spaced from said slot and having supporting connection with the outer end of said shield. 100
7. In a hot air register, a housing, and a grille 45 having a transverse slot at one end thereof and longitudinal slots at the sides thereof, guide rods extending lengthwise of said housing beneath said grille, a shield comprising a plurality of parallel strips flexibly connected one to the other, each strip having its ends bent inwardly to embrace said guide rods, said shield being movable through the transverse slot in said grille, supporting members pivotally mounted at the respective sides of said housing, 50 extending through the respective longitudinal slots and having supporting connection with the outer end of said shield. 105
8. In a hot air register, a housing, a grille having a slot near one end thereof, a flexible shield movable through said slot, means for supporting said shield in an extended position with its upper end above an intermediate portion of said grille, said supporting means being movable to permit said shield to be moved to 60 a position beneath said grille, and a collapsible closure mounted on said housing on each side of said shield for movement into a position to close the space between said grille and said shield when the latter is in its extended position and into a folded position below said grille when said shield is moved beneath said grille. 110
9. In a hot air register, a housing, a grille having a slot near one end thereof, a flexible shield movable through said slot to positions 65 above and below said grille, supporting members 115
- pivotally mounted on said housing at points spaced from said slot and having supporting connection with the outer end of said shield, and a plurality of plates pivotally mounted on said housing at each side of said shield for movement into substantially parallel positions beneath said grille when said shield is moved to a position beneath said grille and for movement into extended positions to close the space between the grille and the shield when the latter is moved to a position above said grille. 120
10. In a hot air register, a housing, a grille having a slot near one end thereof, a flexible shield movable through said slot to position above and below said grille, supporting members pivotally mounted on said housing at points spaced from said slot and having supporting connection with the outer end of said shield, and a plurality of plates pivotally mounted on said housing at each side of said shield for movement into substantially parallel positions beneath said grille when said shield is moved to a position beneath said grille and for movement into extended positions to close the space between the grille and the shield when the latter is moved to a position above said grille. 125
11. In a hot air register, a housing, a grille having a slot near one end thereof, a flexible shield movable through said slot to positions above and below said grille, supporting members pivotally mounted on said housing at points spaced from said slot and having supporting connection with the outer end of said shield, said supporting members having laterally extending parts, and a plurality of plates pivotally mounted at each side of said shield on the axes of the respective supporting members and 130 having parts arranged on the respective sides of their axes for engagement with said laterally extending parts of said supporting members to cause said plates to move with said supporting members. 135
12. In a hot air register, a housing, a grille having a slot near one end thereof, a flexible shield movable through said slot to positions above and below said grille, supporting members pivotally mounted on said housing at points spaced from said slot and having supporting connection with the outer end of said shield, said supporting members having laterally extending parts, and a plurality of plates pivotally mounted at each side of said shield on the axes of the respective supporting members and 140 having parts arranged on the respective sides of their axes for engagement with said laterally extending parts of said supporting members to cause said plates to move with said supporting members, the corresponding parts of said plates being so arranged that they will be engaged one after the other by the supporting members and the several plates at each side of said shield will be successively actuated. 145
13. In a hot air register, a housing, a grille having a slot near one end thereof, a flexible shield movable through said slot to positions above and below said grille and having inwardly extending flanges at the respective sides thereof, a plurality of plates pivotally mounted on a common axis at each side of said shield for movement into substantially parallel positions below said grille and into extended positions above said grille, the outer ends of said plates 150

- overlapping the flanges on the respective sides of said shield, and springs acting on the innermost plates to press the inner plates toward the outer plates.
5. 14. In a hot air register, a housing, a grille having a slot near one end thereof, a flexible shield movable through said slot to positions above and below said grille, supporting members pivotally mounted on said housing at points spaced from said slot and having supporting connection with the outer end of said shield, said supporting members having parts extending inwardly beyond their axes, and devices frictionally engaging said parts to hold said supporting members in the positions to which they have been moved. 80
10. 15. In a hot air register, a housing, a grille having a slot near one end thereof, a flexible shield movable through said slot to positions above and below said grille, supporting members pivotally mounted on said housing at points spaced from said slot and having supporting connection with the outer end of said shield, said supporting members having parts extending inwardly beyond the axes thereof and provided with openings, a pair of resilient fingers embracing each of said parts and having opposed indentations to enter said openings and retain said supporting members in the positions to which they have been moved. 90
15. 16. In a hot air register, a housing, a grille having a slot near one end thereof, and a flexible shield movable through said slot to positions above and below said grille and comprising a plurality of parallel strips arranged edge to edge, and wires extending across and secured to the several strips to flexibly connect said strips one to the other. 95
20. 17. In a hot air register, a housing, a grille having a slot near one end thereof, and a shield movable through said slot to positions above and below said grille and comprising a plurality of parallel strips arranged edge to edge, flexibly connected one to the other, and a spring arranged beneath said grille and acting on one of said strips to move the same toward that end of said housing opposite said slot. 100
25. 18. In a hot air register, a housing, a grille having a transverse slot near one end thereof, and having longitudinal slots near the respective sides thereof and connected with said transverse slots, a supporting member mounted in said housing below said grille, lugs depending from said grille near said transverse slot and engaging said supporting member, a flexible shield movable through said transverse slot to positions above and below said grille, and supporting members pivotally mounted on said housing, extending through the respective longitudinal slots and having supporting connection with said shield. 105
30. 19. In a hot air register, a grille, a flexible shield mounted for movement into positions above and below said grille, and guiding means for so controlling the movements of said flexible shield that it will assume one shape when positioned above said grille and will assume a different shape when positioned below said grille. 110
35. 20. In a hot air register, a grille, a flexible shield mounted for movement into positions above and below said grille, pivoted supporting means connected with the forward portion of said shield to support the same in a curved position above said grille, and guiding means arranged below said grille to guide said shield to a substantially flat position below said grille. 115
40. 45. 50. 55. 60. 65. 70. 75. 80. 85. 90. 95. 100. 105. 110. 115. 120. 125. 130. 135. 140. 145. 150.
